MONOLITHIC, METALLIC-REENFORCED
SLABOctave Schnurer, Pittsburgh, Pa., assignor to
Brixmesh Corporation, Pittsburgh, Pa., a cor-
poration of Pennsylvania

Application January 23, 1932, Serial No. 583,321

1 Claim. (Cl. 72--13)

My invention relates to veneers for application to the external walls of buildings. Primarily, I am concerned with a veneer which may be quickly applied to a wall, and, upon such application, 5 will lend to the wall an appearance of masonry. Broadly, this concept has for years been in the minds of those skilled in the art, but to my knowledge there has been no veneer structure embodying the particularly effective characteristics of 10 my invention.

While the novelty of combination in the appended claims may be of specific nature, it is nevertheless of great practical value. My structure 15 comprises a monolithic, metallic-reenforced slab which has incorporated in its body plaques resembling in elevation the members of the masonry which in service the veneer is to reproduce. It will be observed that an important characteristic of my veneering slab lies in the fact that it 20 includes a plurality of preformed, burnt briquettes (plaque members) spaced apart and arranged in predetermined pattern; the body material of the slab extends into the intervals between the briquettes, so that when installed upon a wall, the 25 wall takes on the attractive appearance of laid brick masonry—practically no “pointing” or “filling in” of the slabs being necessary after installation. In brief, it is only necessary to apply my slabs to a wall, and, without further labor, the 30 wall is attractively finished.

In the accompanying drawings Fig. I is a view in side elevation of a slab embodying the invention, indicating fragmentarily three associated slabs;

35 Figs. II, III and IV are fragmentary views in cross section, to larger scale and taken respectively on the planes II—II, III—III, and IV—IV of Fig. I;

Fig. V is a fragmentary sectional view, to still 40 larger scale, illustrating how the veneer may be conveniently secured to a backing wall;

Figs. VI and VII are views comparable with Figs. I and II, respectively, showing a modification in the structure of the slab veneer;

45 Figs. VIII to XI inclusive illustrate still other modifications; and,

Figs. XII and XIII show a mold fragmentarily, and illustrate how the veneer slabs may be constructed.

50 The veneer structure of my invention comprises a plurality of briquettes 1; the briquettes may be of desired shape and color, and in this case, the briquettes are preformed of clay and burnt in kilns, as standard bricks are made. The briquettes 55 are relatively thin, so that the expanse of bri-

quettes is of slight thickness, conservation of material and minimization of weight being designata. The expanse of briquettes is supported on one face in a monolithic slab 2 of cementitious material, which in this case is a rich, fine concrete. Within its body, extending in the general plane of its expanse, is a metallic reenforcement 3. Light-weight metal lath or other well-known perforate metalsheets may serve as the reenforcement. At various points throughout the slab 10 structure holes 4 are provided for attaching screws or nails. Fig. V illustrates how a nail 5 may be driven through each hole 4 into the backing wall 6 which is to be faced with the veneer. The nail holes lie between the briquettes and are counter- 15 sunk, as indicated—thus mortar 7 can be “spotted” over the nail head.

It is of importance to note that the body of the slab 2 extends into the intervals and provides fillets between the briquettes. All or a portion of 20 the cementitious material forming the body of the slab may be colored when in the “green” state, so that in assembly and in completed state the body of the slab 2, by extending into and appearing within the intervals between the briquettes, lends 25 to the whole, in side elevation, the pleasing appearance of nicely pointed brick masonry. Indeed, the structure practically avoids the necessity of “pointing” which is necessary in all practical slab veneers in use today.

In case the slabs are terminated at their edges intermediate the intervals between alternate briquettes (cf. Fig. I), it will be necessary to fill in and “point” the regions 8 between adjacent slabs, and in the alternate horizontal rows of the 35 briquettes, the side edges of the structure include half briquettes 1a, which upon assembly of the slabs meet in pencil line seams 9. Even this slight pointing operation is eliminated by constructing the edges of the slabs as indicated in 40 Figs. VI and VII. That is, the right-hand edge of the slab A carries the whole fillet 10 for the briquettes of the adjoining edges of the two slabs A and B. The co-operating half-briquettes 1a are, of course, of unequal dimensions, but the 45 structure is, manifestly, one readily to be constructed and installed.

Figs. VIII and IX show still another edge construction for the slabs; it is this: Instead of including half-briquettes 1a in the alternate horizontal rows of briquettes, I form in the monolithic bodies 2 of the slabs recesses 11, such that when the veneer slabs are assembled the several recesses 11 become paired in registry, providing a pocket for the subsequent insertion of bri- 55

quettes 12 (cf. Fig. IX). The briquettes 12 are "buttered" with mortar on their rear faces and inserted in the pockets (11-11) thus provided. Accordingly, the finished application of veneer, even upon close observation has a uniform regular and pleasing appearance.

Figs. X and XI illustrate in cross section how the briquettes (1b and 1c) may be variously fashioned to decrease their weight and conserve the ceramic material of which they are formed. Additionally, the bonding between the body 2 and briquettes may be in this manner increased.

The construction of my veneer may advantageously be effected in a mold 13, in whose bottom a plurality of shallow pockets 14 is provided, so disposed with respect to one another as the briquettes are desired to be in the finished product. The briquettes are placed in the pockets, the pockets being of less depth than the briquettes. Next, the cementitious material, suitably prepared with the desired coloring is spread over the briquettes within the mold, see Fig. XII, and the intervals between the briquettes are provided with molded fillets which, due to the structure of the mold terminate inwardly of the faces of the briquettes that are exposed in the finished structure. That is, the metallic reenforced monolithic slab is applied to the one face of the expanse of briquettes, and said slab includes in its structure molded fillets which extend into the intervals between the briquettes and terminate inwardly of the opposite faces of said expanse. Conveniently, the initial application of material may terminate flush with or slightly above the top faces of the briquettes in the mold. Then the metal reenforcement 3 (Fig.

XIII) is laid in position, and the remainder of the mold filled, on top of the reenforcement, with a cement mix of less expensive nature. I contemplate that the last application of cementitious material may be in the form of uncolored grout, but, of course, a slab 2 built completely of the colored material lies within the invention. As indicated in dotted lines, pegs or pins 15 may be positioned in the mold, either before or after casting the slab, to provide the nail holes 4 alluded to above.

I claim as my invention:

A panel for finishing the external walls of a building comprising a thin monolithic body of solidified mortar including in the plane of its 15 expanse a cancellate sheet of metallic reenforcement, a plurality of thin bricks of fired clay embedded in said mortar, said fired bricks being in the expanse of said monolithic body arranged in staggered relation in the same general manner 20 that the bricks or blocks of ordinary masonry are staggered in side elevation, said thin bricks being spaced apart in the general plane of their expanse, brick pointed molded fillets cast and hardened in the spacing between said bricks and 25 in monolithic integration with said body to constitute said panel a thin pointed brick unit, the edge of said panel being provided with recesses of a depth equal to the depth of the pointed and finished fillets cast between the bricks and being 30 adapted in assembly for registering with the complementary recesses of adjoining panels to provide together pockets for the reception of whole bricks to overlie the lines of abutment of the panels.

OCTAVE SCHNURER.
